EXPLOSIVE COMBUSTION BOILER

John C. Doucha, Chicago, Ill.

Application March 11, 1933, Serial No. 660,393

6 Claims. (Cl. 122—24)

The invention relates to boilers and more particularly to explosive combustion boilers.

The invention is embodied in a boiler adapted to burn either gas or gasified liquids or oils forming an explosive mixture under approximately atmospheric pressure.

An object of the invention is the provision of a highly efficient automatically operative explosive combustion boiler of the kind described.

10 The invention contemplates the use of submerged combustion chambers, and of fire tubes of relative small diameter and of substantial length through which the hot gases released from the combustion chambers are driven at high 15 velocity to overcome the skin friction of the tubes. The efficient length of the boiler is thereby increased and as a result, its depth for a given capacity may be reduced. The pressure of the 20 gases of combustion is such that after giving up their heat to the surrounding water, they have a 25 velocity sufficiently high that they may be discharged through an exhaust pipe and a stack is unnecessary. Furthermore, no fire box is required and the boiler can be positioned close to 30 the floor. The combination of a low depth boiler 35 another object of the invention is the provision of an improved boiler of the kind described which has a low depth for a given capacity and has as a result, a high thermal efficiency.

The invention is embodied in an explosive combustion boiler having no movable mechanism other than automatically actuated valves which are relatively noiseless in operation and a further object of the invention is the provision of an improved explosive combustion boiler which 40 is automatically self charging and operable by changes in pressure differentials therein, and which is substantially noiseless in operation.

Still another object is the provision of improved means connecting a pair of explosive combustion chambers with an exhaust member in a manner whereby the discharge of gases of combustion under pressure from one of said chambers induces a low vacuum in the other of said chambers and vice versa.

50 Still another object of the invention is the provision of an improved boiler of the kind described which is durable, simple in construction, conveniently assembled, economically manufactured and in its construction, assembly and use 55 provides improvements and conveniences not

heretofore employed in the art for the same general purpose.

Many other objects and advantages of the construction herein shown and described will be 60 obvious to those skilled in the art from the disclosure herein given.

To this end, my invention consists in the novel construction, arrangement and combination of parts herein shown and described, and more particularly pointed out in the appended claims. 65

In the drawings, wherein like reference characters indicate like or corresponding parts:

Fig. 1 is a view along the line 1—1 of Fig. 2, the same being a longitudinal vertical sectional view through a boiler embodying the principles 70 of my invention;

Fig. 2 is a partial sectional and front end view of the boiler shown in Fig. 1;

Fig. 3 is a view along the line 3—3 of Fig. 2 drawn to a larger scale; 75

Fig. 4 is a view along the line 4—4 of Fig. 1;

Fig. 5 is a view along the line 5—5 of Fig. 1;

Fig. 6 is a view along either lines 6—6 or lines 6a—6a of Fig. 4; and 80

Fig. 7 is a view along the lines 7—7 of Fig. 6.

Referring now more particularly to the drawings, the boiler comprises a cylindrical shell 8 having a curved rear end wall 9 and a front end wall 10. Feed water is admitted into the boiler from the rear through an inlet pipe 11 and the steam generated by the boiler is discharged from the top through a pipe 12. 85

The boiler shell 8 is positioned in closely spaced apart relation to a floor on a plurality of supporting members 13. A diaphragm 14 positioned 90 towards the rear of the boiler separates a front main steam generating chamber 16 from the rear portion of the boiler. A horizontal diaphragm 15 divides the rear end of the boiler into upper and lower chambers 17 and 18, respectively. An exhaust conduit 19 connected with the chamber 18 provides an outlet for the gases of combustion. The inlet pipe 11 is connected with an economizer, positioned in the chamber 18. The economizer comprises a plurality of branch pipes 20 and headers 21 over and between which the exhaust gases flow before being discharged through the conduit 19. 95

A plurality of longitudinally extending tubes 22 are arranged in a group in the upper portion 100 of the chamber 16 and a larger number of similar tubes 23 are positioned in the bottom portion of the chamber. The ends of the tubes 22 and 23 project through the front wall plate 10 and the diaphragm plate 14. The diaphragm plate 14 105

110

also provides a plurality of apertures 24 permitting circulation of water between the chambers 16 and 17.

A forwardly and upwardly projecting chamber 28 is provided at the front end of the boiler with its lower end connected with the bottom of the chamber 16 by an aperture 40. The chamber 28 is bounded by an inner plate 25, an outer plate 26 and a top plate 27. The top of the chamber 28 is normally below the water level in the main boiler and as a result is constantly filled with water. The chamber 28 provides a preheater for a portion of the water by reason of contact therewith of gases moving downwardly through a chamber 31. The chamber 31 provides a conduit into which hot gases of combustion are discharged for the forward ends of the tubes 22 and enter the corresponding ends of the tubes 23. The upper portion of the chamber 31 is bounded by a plate 29 having flanged edges 32 fastened to the end plate 10 and to the top plate 27 of the chamber 28. The downwardly descending gases are deflected into contact with the inner bounding plate 25 of the chamber 28 by a curved plate 30 fastened to the front wall plate 10 between the open ends of the tubes 22 and of the tubes 23. A vertically extending plate 33, mounted on the middle portion of the plate 29 opposite to the tubes 22, converges rearwardly at its midportion to provide a pair of concave surfaces. The concave surfaces are so arranged that they tend to circulate the descending gases and cause their uniform distribution through the relatively wide lower portion of the chamber 31.

The boiler is so constructed that combustion occurs below the normal water level and also gases of combustion travel through conduits below the water level surrounded entirely by water except for the chamber 31 which is substantially so surrounded. A longitudinally extending tubular member 34 is positioned below the water level on one side of the chamber 16 with its front end projecting through the plate 10. The member 34 converges at its rear end to provide a conical member 36 opening through the diaphragm 14. A tubular member 35 similar to the member 34, also below the water level, is oppositely positioned in the chamber 16 with its front end projecting through the plate 10 and its rear end converging to provide a conical member 37 opening through the diaphragm plate 14. The members 34 and 35 provide combustion chambers 38 and 39 respectively. The rear ends of the chambers 38 and 39 are connected with the tubes 22 by conduits 41 and 42, respectively. The conduits 41 and 42 respectively terminate in closely spaced discharge nozzles 43 and 44 positioned in a forwardly converging member 46 providing an exhaust nozzle. The rear end of the member 46 is closed by a plate 47 and its forward end is connected with a conical-shaped member 48 providing a chamber 49 opening into the rear ends of the tubes 22. Branch pipes 52 and 53 are provided to form by-passes connecting the intermediate portions of the conduits 41 and 42 with the exhaust member 46. The pipes 52 and 53 open into the member 46 adjacent the discharge nozzles 43 and 44, respectively. Flow of gases through the by-pass pipes 52 and 53 is controlled by valves 54 and 55, respectively. The member 46 is connected with the atmosphere by a tube 50 opening into the member above and rearwardly of the discharge nozzles 43 and 44. A valve 51 is operable to control the flow of air through the pipe 50 into exhaust chamber 46.

The connections of the exhaust member 46 with the conduits 41 and 42, the by-pass pipes 52 and 53 and the chamber 49 are such that they are sealed against entrance of water and water vapor with which such elements are surrounded. The valves 54 and 55 are identical and are shown in detail in Figs. 6 and 7 as each comprising upper and lower longitudinally extending sections, respectively numbered 100 and 101. The sections 100 and 101 have flanged edges 102 separated by gaskets 103, clamped together by bolts 104 to provide a fluid tight valve body. The valve body terminates at each end in an annular flange 105 fastened by bolts 106 to corresponding flanges 107 formed on the contiguous by-pass sections between which the valve body is interposed.

The intermediate portion of the valve body is enlarged to provide a chamber 108 having a cover 109 clamped thereon by bolts 110 to provide a fluid tight joint. The oppositely positioned valves 54 and 55 are so arranged that the bottom of the chamber 108 of each is inclined upwardly towards the exhaust chamber 46 and provides a seat for the ball 111. The inclination of the bottom wall and the weight of the ball 111 are so adjusted that the ball occupies the full-line position except when the pressure in the pipe section 52 connecting the chamber 108 with the exhaust chamber 46 is lower by a predetermined amount than the pressure in the pipe section 52 connecting the chamber 108 with the conduits 41 or 42, in which event the ball is moved to its dotted line position and prevents flow of gases therethrough into the chamber 46. Upon the pressure differential becoming less than the predetermined amount, the ball 111 returns to its full line or open position of the valve.

A pair of spaced apart plates 112 provide guides for the ball 111 in its movement to closed position and a bar 113 positioned above and extending transversely to the path of the ball prevents the latter from being elevated to the top of the chamber 108.

Separate sets of similar closure elements, mounted on the projecting front ends of the tubular members 34 and 35, provide means for conveying a mixture of fuel and air into the respective combustion chambers 38 and 39 formed by the tubular members. The closure elements each include a disc plate or block 56 fastened in any suitable manner to the end of the tubular members 34 and 35. The plates 56 each provide a central aperture 57 having a tapering edge 58 forming a seat for a valve 59. A circular bore 60 in the plate 56 is connected with the aperture 57 by a plurality of discharge ports 61 terminating in the valve seat 58. An inlet duct 62, opening into the bore 60 and controlled by a regulating valve 63 provides an inlet for fuel such as gasoline or oil to be discharged through the bore 60 and ports 61. A gasoline feed pipe 66 discharges into the valves 63 through branch pipes 67. Valves 68 are provided to control the flow of gasoline through the branch pipes 67. A fuel oil pipe 69 controlled by a valve 70 is also connected with each of the valves 63. Housings 71, preferably concentric with the apertures 57, are mounted on the exterior of each plate 56 to provide chambers 72 respectively opening into the combustion chambers 38 and 39 through the apertures.

A valve 80 on the underside of each of the housings 71 provides an inlet for air into the housings and combustion chambers 38 and 39 through

the apertures 57. The valves 80 are each mounted in a housing 81 and are normally held in open position by a spring 82. Inwardly converging plates 92, mounted on the inner face of the blocks 56 are apertured and otherwise constructed to act as atomizers tending to vaporize the fuel coming through the ports 61 and mix the same with the air admitted through the valve 80.

Means is also provided for admitting air under pressure into the chambers 72 for initial charging of either of the combustion chambers 38 and 39. For this purpose, a main compressed air pipe 73 is connected with the chambers 72 by branch pipes 74 controlled by valves 75. The valves 59 each have an elongated stem 76 extending through the chamber 72 and projecting through the end wall of the housing 71. A compression spring 79, having its ends respectively abutting the end of the housing 71 and a washer 78, adjustably positioned on the stem 76 by a nut 77, comprise means normally holding the valves 59 in closed position.

The explosive mixtures in the combustion chambers 38 and 39 are respectively ignited by a plurality of spark plugs 90, shown in Fig. 5 as mounted on the shell 8 and operatively connected with the combustion chambers. A plurality of the spark plugs 90 are preferably provided for each of the combustion chambers 38 and 39 arranged in spaced apart relation and in sufficient numbers that the entire contents of the chamber will be simultaneously ignited. Movement of either of the valves 59 to closed position energizes the spark plugs so connected with the combustion chamber by closing a circuit connecting the spark plugs with an induction coil (not shown). The circuits each comprise a conductor 88 having one end connected with the induction coil and the other end connected with an adjustable contact member 86. The contact members 86 are mounted on the inturned ends 85 of bars 84 suitably fastened to the plate 56. The contact members 86 are positioned in longitudinal alignment with and in spaced apart relation to the projecting end of the corresponding valve stem 76. Resilient contact members 87 are mounted on the bars 84 with their free ends projecting between the ends of the contact members 86 and the adjacent ends of the valve stems 76, the latter having their contacting ends insulated. Separate sets of conductors 89 connect the contact members 87 with the spark plugs 90 of the corresponding combustion chamber. Movement of the valve 59 to closed position causes the insulated end of the stem 76 to contact with and bend the resilient contact member 87 sufficiently that the latter engages the contact member 86, thereby closing the circuit and energizing the spark plugs 90 with the result that the explosive contents of the combustion chamber are ignited.

The preliminary steps in charging the boiler in cold state with fuel are as follows: Either of the combustion chambers 38 or 39 is filled with an explosive mixture of compressed air and gasoline, it being a matter of indifference which of such chambers are so charged. Assuming that the combustion chamber 38 is selected as the one to be initially charged, the fuel oil valves 70 are both closed and the gasoline valve 68 connected with the chamber 72 opening into the combustion chamber 39 is also closed. The valve 68 controlling the branch pipe 67 opening into the valve 68 controlling the flow of fuel into the combustion chamber 38 is open. Gasoline is fed into the gasoline supply line 66 from an overhead tank

(not shown) by gravity or under low pressure. The valve 75 controlling the branch air pipe 74 opening into the chamber 72 connected with the combustion chamber 39 is closed and the valve 75 controlling the branch pipe 74 opening into the chamber 72 connected with the combustion chamber 38 is open. With the valves 75 respectively closed and open as described, a measured quantity of compressed air from a tank (not shown) is introduced into the chamber 72 connected with the combustion chamber 38. The pressure of the entering air closes the spring valve 80 which under atmospheric pressure is open and opens the valve 59 which under atmospheric pressure is held closed by means of the spring 79. The opening of the valve 59 uncovers the fuel ports 61 allowing the gasoline to mix with the compressed air and fill the combustion chamber 38 with the explosive mixture. The measuring tank containing compressed air is preferably so constructed and of such capacity that the pressure therein drops to approximately one pound above atmospheric when the combustion chamber 38 is substantially filled with

explosive mixture at atmospheric pressure or slightly above. The open valve 75 is then closed and the pressure in the chamber 72 is permitted to drop to a point where the valve 59 closes. The closing of the valve 59 also closes the circuit connected with the spark plugs 90 operatively connected with the combustion chamber 38. The resulting ignition of the explosive mixture in the chamber 38 raises the pressure of the gases contained therein preferably to approximately one hundred pounds, the degree of pressure depending upon the richness of the mixture and the size of the outlet pipe 41 and the nozzle 43. The sudden rise in pressure in the chamber 38 closes the valve 54 in the by-pass pipe 52, the latter being preferably so adjusted as to close at a differential of approximately ten pounds. The hot gases are then discharged only through the pipe 41 and nozzle 43 into the exhaust member 46, the latter being so constructed as to cause the flow to produce a vacuum zone in its rear end portion with which the pipes 52 and 53 are connected. The exhaust member 46 is shown as providing a single stage nozzle but a multiple stage nozzle may be used, if desired. Regulation of the vacuum in the combustion chamber and also in the exhaust member 46 may be accomplished by means of the valve 51 which controls the pipe 50 connecting the member with the atmosphere. The hot combustion gases are discharged from the nozzle 43 at a high velocity by reason of the pressure in the chamber 38. The gases then pass through the chamber 49 where they spread out and enter the tubes 22 at a relatively high rate, and are discharged therefrom into the chamber 31 and then out through the tubes 23 as already described.

The pressure in the conduit 41 and the vacuum in the exhaust member 46 maintains the pressure valve 54 in closed position while the pressure valve 55 in the by-pass pipe 53 is in open position during the exhaust of the hot gases from the chamber 38. The combustion chamber 39 is simultaneously exhausted of its air contents through the by-pass pipe 53 and the pipe 42 thereby producing vacuum in the combustion chamber 39. The vacuum or pressure below atmosphere in the chamber 39 will result in the outside air opening its valve 59 and permitting air at atmospheric pressure to enter through the aperture 57 to replace that exhausted through the

member 46. This inflowing air mixes with the gasoline flowing through the ports 61 when the valve 59 is open and as a result, the combustion chamber 39 is charged with an explosive mixture upon completion of the described combustion and exhaust of gases from the chamber 38. When the pressure in the chamber 39 becomes approximately that of the atmosphere, its valve 59 is closed by the action of the spring 79 and causes ignition of the mixture by energizing the spark plugs 90 operatively connected with the chamber 39. Discharge of the gases of combustion from the chamber 39 into the exhaust member 46 opens the valve 54 in the by-pass pipe 52 which results in the exhaustion of the chamber 38 to a point where its control valve 59 opens and admits a mixture of air and gasoline. This cycle of alternate combustion, exhaustion and charging is automatically repeated thirty to one hundred times per minute in each combustion chamber, the rate depending upon the size of the discharge nozzles 43 and 44 and the richness of the mixture. Following the initial charge of the selected combustion chamber by the use of compressed air, the device operates automatically at atmospheric pressure to alternately produce the described cycle of operations in each of the chambers 38 and 39. The by-passes 52 and 53, controlled by the valves 54 and 55 respectively, are provided to accelerate the discharge of the gases from the explosion chambers with which they are connected. The areas of the nozzles 43 and 44 are necessarily restricted in order that they may create the requisite vacuum in the exhaust chamber 46. The by-passes 52 and 53, by opening following the initial exhaust of the explosion chambers with which they are respectively connected, shorten the time within which the explosion chambers are exhausted.

The explosion of hydro-carbon fuels in the combustion chambers 38 and 39 results in the combination of the hydrogen content of the fuel with excess oxygen to form water vapor which condenses and creates a partial vacuum in the combustion chamber after the initial high pressure drops below the saturation point. The exhaust member connected as described with the other combustion chamber through its discharge and by-pass pipes increases this vacuum effect and results in the introduction of more of the explosive mixture into the combustion chamber than could otherwise be the case.

After the combustion chambers 38 and 39 are warmed up by using gasoline as fuel, the gasoline line may be cut out and the boiler then operated with heavier and cheaper fuel oils. In changing from gasoline to the heavier hydrocarbons as fuel, the valves 68 will be closed and the valves 70 which control the oil pipes 69 will be open. The oil pipes 69 are connected with a supply of oil (not shown) so positioned and controlled that the oil flows into the device either by gravity or under pressure sufficient to accomplish delivery of the oil through the ports 61 when the valve 59 is open. The oil discharged from the ports 61 will be mixed in the aperture 57 with the stream of inflowing air, the mixture contacting with the atomizer plate 92 which has been heated by the described operation of the boiler with gasoline as fuel to a temperature sufficiently high to vaporize the oil and provide an explosive mixture of substantially uniform richness and density.

The thermal efficiency of a boiler constructed and automatically operable as described is rela-

tively high, this being due in part to the high initial pressure of the ignited gases and the resulting velocity with which they are discharged through a large number of the relatively long small diameter tubes 22 and 23 without being retarded by skin friction and also to the low vacuum in the combustion chamber as a result of the substantially complete evacuation of the gases of combustion. The number and arrangement of the tubes 22 and 23 are such that the heat of the gases is transmitted to the surrounding water while traveling at a velocity greater than would be possible under ordinary draft conditions with the further advantage that the velocity at the point of discharge from the tubes 23 is such that a stack is not needed and the gases may be discharged through a relatively small exhaust pipe. The rapid expansion of the gases also releases the thermal energy more rapidly than is the case where combustion occurs under constant pressure and as a result, thermal efficiency of a boiler so constructed and operable as described is in some cases, higher than ninety percent.

Thus, it will be seen that I have provided an improved explosive combustion boiler of the kind described which is automatically operable, highly efficient, relatively noiseless and adapted for use either for heating purposes or the generation of power.

Having thus described the invention, it is obvious that various immaterial modifications may be resorted to without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a boiler of the kind described, a pair of explosion chambers each provided with a discharge conduit, means for alternately producing explosion in said chambers, and exhaust chamber, a pair of by-pass pipes respectively connecting the explosion chambers with the exhaust chamber, said discharge conduits extending into the exhaust chamber and terminating beyond said pipes to provide a vacuum zone adjacent the discharge ends of said pipes, and a pair of pressure control valves positioned one in each of said pipes, said valves each automatically operable to close when the pressure in the inlet end of its pipe exceeds the pressure in the outlet end thereof by a predetermined amount and to open when said pressure differential is less than said predetermined amount.

2. In a boiler of the kind described, a receptacle for water, heating means submerged in the water contents of the receptacle, said means comprising a pair of explosion chambers each provided with a discharge conduit, means for alternately producing explosion in said chambers an exhaust chamber, a pair of by-pass pipes respectively connecting the explosion chambers with the exhaust chamber, said discharge conduits extending into the exhaust chamber and terminating beyond said pipes to provide a vacuum zone adjacent the discharge ends of said pipes, and a pair of pressure control valves positioned one in each of said pipes, said valves each automatically operable to close when the pressure in the inlet end of its pipe exceeds the pressure in the outlet end thereof by a predetermined amount and to open when said pressure differential is less than said predetermined amount.

3. In a boiler of the kind described, a pair of

- explosion chambers each provided with a discharge conduit, an exhaust chamber, a pair of by-pass pipes respectively connecting the explosion chambers with the exhaust chamber, said discharge conduits extending into the exhaust chamber and terminating beyond said pipes to provide a vacuum zone adjacent the discharge ends of said pipes, a pair of pressure control valves positioned one in each of said pipes, said valves each automatically operable to close when the pressure in the inlet end of its pipe exceeds the pressure in the outlet end thereof by a predetermined amount and to open when said pressure differential is less than said predetermined amount, and means automatically operable to alternately deliver to each explosion chamber a mixture of fuel and air during evacuation of its gases of combustion through its by-pass pipe, said means operable to ignite said mixture upon completion of its delivery.
4. In a boiler of the kind described, a pair of explosion chambers each provided with a discharge conduit, an exhaust chamber, a pair of by-pass pipes respectively connecting the explosion chambers with the exhaust chamber, said discharge conduits extending into the exhaust chamber and terminating beyond said pipes to provide a vacuum zone adjacent the discharge ends of said pipes, a pair of pressure control valves positioned one in each of said pipes, said valves each automatically operable to close when the pressure in the inlet end of its pipe exceeds the pressure in the outlet end thereof by a predetermined amount and to open when said pressure differential is less than said predetermined amount, and means automatically operable to alternately deliver to each explosion chamber a mixture of fuel and air at atmospheric pressure during evacuation of its gases of combustion through its by-pass pipe, said means operable upon completion of said alternate delivery to automatically ignite said mixture.
5. In a boiler of the kind described, a receptacle for water, heating means submerged in the water contents of said receptacle, said means comprising a pair of explosion chambers each provided with a discharge conduit, an exhaust chamber, a pair of by-pass pipes respectively connecting the explosion chambers with the exhaust chamber, said discharge conduits extending into the exhaust chamber and discharging in a direction adapted to produce a vacuum zone adjacent the discharge ends of said pipes, a pair of pressure controlled valves positioned one in each of said pipes, said valves each automatically operable to close when the pressure in the inlet end of its pipe exceeds the pressure in the outlet end thereof by a predetermined amount and to open when said differential pressure is less than such predetermined amount, a plurality of tubes each providing an outlet for said exhaust chamber, and means automatically operable to alternately deliver into each explosion chamber a mixture of fuel and air during evacuation of its gases of combustion through its by-pass pipe, said means operable upon completion of said alternate delivery to automatically ignite said mixture.
